(57) **CLAIM**

We claim the ornamental design for an electronic toy house, as shown and described.

DESCRIPTION

FIG. 1 is a front perspective view of an electronic toy house showing our new design.

FIG. 2 is a front view of the electronic toy house of FIG. 1.

FIG. 3 is a rear view of the electronic toy house of FIG. 1.

FIG. 4 is a top view of the electronic toy house of FIG. 1.

FIG. 5 is a bottom view of the electronic toy house of FIG. 1.

FIG. 6 is a right side view of the electronic toy house of FIG. 1; and,

FIG. 7 is a left side view of the electronic toy house of FIG. 1.

The broken lines shown in the drawings are for illustrative purposes only and form no part of the claimed design.

1 Claim, 5 Drawing Sheets
